UNITED STATES PATENT OFFICE

WARREN G. HAMILTON, OF ATLANTIC CITY, NEW JERSEY, ASSIGNOR OF ONE-HALF TO
JOSEPH GINSBURG, OF PHILADELPHIA, PENNSYLVANIA; GERTRUDE HAMILTON
ADMINISTRATRIX OF SAID WARREN G. HAMILTON, DECEASED

SAFETY ATTACHMENT FOR TYPOGRAPHICAL COMPOSING AND CASTING MACHINES

Application filed March 12, 1927. Serial No. 174,768.

My invention relates to typographical machines of the general character and organization disclosed in U. S. Letters Patent No. 436,532, granted September 16, 1890, for casting integrally, composed lines of type, and particularly machines adapted to employ double letter matrices, and to assemble matrices at either one of two levels, to wit, a lower and an auxiliary level, and my invention relates more particularly to a novel safety device adapted to be attached to the casting vise, and to the delivery channel respectively, of the conventional forms of type casting machines of this character, and adapted to coact with the so called "two letter" attachment, filler piece or "flapper" of such machines and the so called "duplex rail" thereof, in such a manner as automatically to lock the so called "assembling elevator" against any upward movement thereof, if both the two letter attachment or "flapper" and the duplex rail are in their auxiliary positions at the same time.

It is well known, that if, in the operation of machines of this character the matrices are assembled in the assembling elevator in the upper, or auxiliary position, by the use of the so called "duplex rail" and the filler piece or two letter attachment, or the so called "flapper" is then positioned in operative alignment with the so called first elevator, by an oversight on the part of the operator, the matrices will be presented to the casting device of the machine, out of alignment with either one of the two matrix guides thereof.

The results of delivering, or attempting to deliver, matrices into the casting apparatus while misaligned, by the improper joint use of the duplex rail and the filler piece, may be various. Thus the misaligned matrices, upon being delivered into the casting apparatus may be broken or crushed so as to render them incapable of further use, or parts of the casting apparatus are broken by

the excessive strain, or if the matrices are presented in a misaligned position with respect to the casting plate or die, and molten metal is delivered therethrough, such metal will flow past the matrices and squirt out on either side. This latter condition is what is usually termed as a "flapper squirt."

The object of my invention therefore is practically to eliminate any possibility of misalignment of matrices in the casting apparatus or while being delivered to the casting apparatus, by providing novel means cooperating with the filler piece and the duplex rail, so as automatically to lock the assembling elevator against any upward movement, in the event that the duplex rail and filler piece have both been improperly set into their operative or auxiliary positions.

With the above ends in view, my invention consists of a suitable locking bolt slidably mounted, preferably on the bottom of the delivery channel assembly, having a suitable projection, finger or catch member, adapted to interlock or interengage with the near end of the duplex rail of the assembling elevator, when said bolt or slide is in an outer, locking or operative position, and when the duplex rail of the assembling elevator is also in the inner or operative position. My invention further consists of certain actuating means intermediate the filler piece and said slide to displace the latter into said outer operative locking position.

For the purpose of illustrating my invention, I have shown in the accompanying drawings, a form thereof which is at present preferred by me, since it will give in practice, satisfactory and reliable results, although it is to be understood that the various instrumentalities of which my invention consists can be variously arranged and organized and that my invention is not limited to the precise arrangement and organization of these instrumentalities as herein shown and described.

In the accompanying drawings, illustrating my novel safety device for typographical composing and casting machines, and showing the parts of a conventional machine, to which the former is applied and with which the former coacts:

Figure 1 represents a front elevation of a fragmentary portion of a typographical composing and casting machine, or particularly a front elevation of the first elevator, casting vise, delivery channel and assembling elevator, to which the novel safety device, embodying my invention is attached.

Figure 2 represents a top plan view, partly in section taken on line 2—2 of Figure 1.

Figure 3 represents a top plan view of the safety device embodying my invention, shown detached from a conventional machine, and showing also the interlocking 20 of the same, with the duplex rail.

Figure 4 represents a vertical section on line 4—4 of Figure 1, on a greatly enlarged scale, illustrating the outer or inoperative position of the duplex rail.

Figure 5 represents a section similar to that shown in Figure 4, illustrating the inner or inoperative position of the duplex rail.

Figure 6 is a fragmentary plan view of 30 the duplex rail in the inner, operative or auxiliary position, and of the locking slide of my novel safety device, also shown in the outer or auxiliary operative position, and in locking engagement with said duplex rail.

Figure 7 represents a perspective view of 35 my novel safety device, shown detached from a conventional typographical composing and casting machine, illustrating the relation thereof to the filler piece at one end, and the duplex rail at the other end.

Figure 8 represents a perspective view of a die or casting plate, of a conventional machine showing the two matrix guide channels thereof.

Figure 9 represents a side elevation in section of a casting die with a matrix abutting the face thereof in the lower aligned position as normally presented without the use of either duplex rail or filler piece.

Figure 10 represents a similar side elevation to that shown in Figure 9, with a matrix abutting the face of the die in the upper or auxiliary position, as presented by the separate use of either the duplex rail 55 or the filler piece.

Figure 11 represents a similar side elevation in section, of the die or casting member and showing the position of a matrix relative to said die member, as a result of 60 the improper combined or simultaneous use of both filler piece and duplex rail, against which the novel safety device of my invention is adapted to guard.

In carrying out my invention, I provide 65 a slide 1, having a pair of elongated and

preferably aligned spaced apertures 2 and 3, through which a pair of corresponding fastening screws 4 and 5 may be passed, which are then threadedly anchored in suitable threaded apertures in the lower portion 6 of the delivery channel assembly 7

70

of a conventional typographical composing and casting machine of the character stated. By this means, the slide 1 is mounted upon the lower horizontal surface of said de-

75

livery channel assembly 7, in a slideable manner, being capable of longitudinal displacement corresponding to the effective length of the apertures 2 and 3. One end of the

80

slide 1 carries an upright locking member or catch 9, extending at a right angle to the slide 1, and preferably formed integral with therewith, by merely bending up a suitable portion of metal of which the slide is formed; said catch 9 having a suitable lower and substantially horizontal locking

85

shoulder or ledge 10, disposed in operative alignment with the corresponding terminal portion 11 of the duplex rail 12, of the conventional form of machine, when said duplex rail is in the inner or auxiliary position.

90

The catch member 9 is so positioned with respect to the inner edge 13 of the duplex rail 12, that said edge 13 will clear said catch 9, when the duplex rail is in the outer or normal position thereof and so that the terminal portion 11 of said duplex rail 12 will be brought into operative alignment with the catch 9 when said rail is in the inner auxiliary position.

95

Moreover, the extreme edge 14 of the catch 9 is so positioned with respect to the edge 15 of the terminal portion 11 of the duplex rail 12, that said edge 15 will clear the edge 14 of the catch 9 when the slide is in the retracted or inoperative position shown in Figure 7, and so that said terminal portion 11 of the duplex rail 12 is in operative alignment with the catch 9 when the slide 1 is in the right hand or operative position thereof.

105

In order to retain the slide 1 and hence the catch 9 normally in the retracted position (shown in Figure 7) a suitable tension spring 16 may be interposed between the head 17 of the stationary screw 4 and a suitable anchor 18 fixedly secured to the slide 1.

110

The outer end of the slide 1 is provided with a downwardly extending vertical flange 19, disposed substantially at a right angle to the slide 1 and preferably formed integral with therewith and having a suitably inclined or curved lip portion 20.

115

In order to actuate the slide 1, that is, to displace the same in a direction towards the terminal portion 11 of the duplex rail 12, whenever the filler piece 21 is positioned in the auxiliary or operative position, I pro-

120

125

130

vide a suitable eccentric member 22 fixedly secured to the shaft or spindle 23 of the filler piece 21. The eccentric member 22 is provided with an annular peripheral groove, in which is seated an annular eccentric strap 24, carried at one end of an actuating rod 25; the opposed end of which is provided with a downwardly extending right angular pivot pin 26.

10 A suitable bracket 27, having an upper horizontal portion 28, is secured to any suitable portion of the casting vise 29, by means of the screw 30. Upon the upper horizontal portion 28, a rocker arm 31 is pivotally secured, by means of the pivot screw 32, so as to permit of oscillation or deflection thereof about a vertical axis. The front end 33 of said rocker arm 31 is provided with a suitable aperture 34, which is 15 adapted to receive the pivot pin 26 of the actuating rod 25, whereby a pivotal connection may be maintained between the rocker arm 21 and said rod 25. The rear portion 35 of the rocker arm 31 in turn is provided with a curved or inclined terminal edge 36, in juxtaposition to the curved lip portion 20 of the vertical flange 19 carried by the slide 1 and is adapted to bear against the latter when the rocker arm 31 is deflected by the 20 rotation of the eccentric member 22, as will be seen from Figure 7.

25 It will thus be seen, that if the filler piece 21, carried by the shaft or spindle 22, is positioned in the right hand or operative position, the rocker arm 31 will be deflected, with the rear portion 35 thereof displacing the slide 1, against the tension of the spring 16 in the direction of the duplex rail 12. If the matrices 37 are thus assembled in the 30 lower or normal position shown in Figure 4, with the duplex rail 12 retracted, the assembling elevator will be free to move in an upward direction, because the edge 13 of the duplex rail 12 will clear the catch 9, even 35 though said catch has been displaced towards the duplex rail 12 in the direction of the arrow 38, by means of the eccentric 22 and the rocker arm 31. The matrices thus assembled will, due to the action of the 40 filler piece 21, be presented to the casting vise 39, in the upper or auxiliary position shown in Figure 10. If on the other hand, the filler piece 21 is also in the auxiliary or right hand position, and the duplex rail 12 is set 45 into the inner or auxiliary position, so as to assemble the matrices 37 in the upper or auxiliary position shown in Figure 5, then the terminal portion 11 of the duplex rail 12, will be positioned directly beneath the horizontal ledge or shoulder 10 of the catch 9, so as to be encountered thereby when the 50 assembling elevator 40 is attempted to be raised. This interengagement of the catch 9 and the terminal portion 11 of the duplex rail 12, automatically locks the assembling

elevator 40 before it can reach its upper or delivering position, thereby preventing the matrices 37 from being presented to the die 39 in the misaligned position shown in Figure 11.

Having thus described my invention, what I claim as new and desire to secure by Letters Patent is:—

1. In a typographical composing and casting machine of the class including a matrix assembling elevator and a retractile rail for supporting the matrices, capable of being set to cause assembling of matrices at relatively different levels in said assembling elevator, and level regulating means including a manually operable pivot capable of being rotated into two different positions, to present lines of assembled matrices at relatively different levels to the casting mechanism, a safety device governed by the setting of both said retractile rail and said level regulating means, including eccentric means carried by said manually rotatable pivot, and a spring-retracted catch-slide operable by said eccentric against the force of the retracting spring thereof, said catch-slide being in operative alignment with said rail when said rail is in its inner position, and being out of alignment with said rail when the latter is in its retracted position, and being adapted to engage said rail, thereby to lock said matrix assembling elevator against upward movement when advanced towards the rail against the force of the retracting spring thereof, while said rail is in its inner position.

2. In a typographical composing and casting machine of the class including a matrix assembling elevator and a retractile rail for supporting the matrices, capable of being set to cause assembling of matrices at relatively different levels in said assembling elevator, and level regulating means including a manually operable pivot capable of being rotated into two different positions, to present lines of assembled matrices at relatively different levels to the casting mechanism, a safety device governed by the setting of both said retractile rail and said level regulating means, including eccentric means carried by said manually rotatable pivot, a spring-retracted catch-slide operable by said eccentric against the force of the retracting spring thereof, said catch-slide being in operative alignment with said rail when said rail is in its inner position, and being out of alignment with said rail when the latter is in its retracted position, and being adapted to engage said rail, thereby to lock said matrix assembling elevator against upward movement when advanced towards the rail against the force of the retracting spring thereof, while said rail is in its inner position, an eccentric strap surrounding said eccentric, a connecting rod

extended therefrom, a lever arm pivotally mounted intermediate of its ends, having one end thereof pivotally connected to said connecting rod and having the other end 5 thereof in operative alignment with said catch-slide while the composing and casting machine is in an operating condition, and being adapted, when deflected by said eccentric, to urge the catch-slide towards 10 said rail against the force of the retracting spring thereof.

3. In a typographical composing and casting machine the combination of assembling elevator, wherein the matrices may be composed in an upper and a lower position, a device adjustable to an active and an inactive position to determine the level at which the composed line of matrices are presented to the mould, said device including a manually rotatable pivot and means for automatically locking the elevator by direct engagement therewith, against movement from its composing position when matrices occupy the upper level therein, and said device is in the active position, said automatic locking means including eccentric means carried by said pivot, and a catch-slide operated by said eccentric means and being adapted directly to engage, in its advanced 25 position, the assembling elevator whenever matrices are composed therein in the upper position.

4. In a typographical composing and casting machine, the combination of an assembling elevator wherein matrices may be composed in an upper and lower position, a device adjustable to active or inactive position to determine the level at which the composed matrices are presented to the mold, 35 said device including a manually rotatable pivot and means controlled by said device for automatically locking the elevator by direct engagement therewith against movement from its composing position when matrices occupy the upper level therein and said device is in active position, said automatic elevator locking means including eccentric means carried by said pivot, a catch-slide adapted for direct locking engagement 45 with said elevator, and a connecting rod and rocker arm operatively interposed between said eccentric means and said catch-slide.

5. In a typographical composing and casting machine, the combination of an assembling elevator provided with a retractible rail for supporting composed matrices in an upper position therein, a pivotally supported and pivotally operable stop member adjustable to active or inactive position to 55 determine the level at which the composed matrices are presented to the mold, and a safety device operative in the active position of said stop member and elevator rail to engage the latter directly and lock the elevator against movement, including eccentric 60

means carried by and operated by the pivot of said stop member, a spring-retracted catch adapted to engage said retractible rail, and an eccentric rod and rocker-arm operatively interposed between said eccentric means and said catch for causing the former to operate the latter. 70

In witness whereof I have hereunto set my hand this 8th day of December 1926.

WARREN G. HAMILTON.
